 Golan Christie Taglia LLP(57) **CLAIM**

The ornamental design for a scope reticle, as shown and described.

DESCRIPTION

FIG. 1 is a front view of a scope reticle in accordance with the invention;

FIG. 2 is a front view of the scope reticle of FIG. 1 with a scope and environment shown in broken lines; and,

FIG. 3 is a back view of the scope reticle of FIG. 1 with a scope and environment shown in broken lines.

The evenly broken lines in the FIGS. 2 and 3 disclose unclaimed environment only; the dash-dot broken lines in the FIGS. 2 and 3 disclose unclaimed boundary of the views only. The broken lines form no part of the claimed design.

1 Claim, 3 Drawing Sheets

FIG. 1

FIG. 2

FIG. 3
